UNITED STATES PATENT OFFICE.

CHARLES M. JOHNSON, OF NEW YORK, N. Y.

MOTOR-VEHICLE.

SPECIFICATION forming part of Letters Patent No. 609,811, dated August 30, 1898.

Application filed December 22, 1896. Serial No. 616,633. (No model.)

To all whom it may concern:

Be it known that I, CHARLES M. JOHNSON, a citizen of the United States of America, residing at 689 Green street, in the city, county, 5 and State of New York, United States of America, (but temporarily residing at London, England,) have invented new and useful Improvements in Motors and in Motor-Vehicles, of which the following is a specification.

10 My invention relates to motors propelled by petroleum or other explosive material or gas and to motor-vehicles to be propelled thereby.

In the accompanying sheets of drawings, Figure 1, Sheet 1, is a sectional plan showing 15 the general arrangement. Fig. 2 is a section through the fore-carriage, showing the ball-race. Fig. 3 is a section on the line 3 3, Fig. 1. Figs. 4 and 5 are detail views, on an exaggerated scale, showing an arrangement to prevent the driving-wheels from skidding. Fig. 20 6, Sheet 2, is a section of a road-wheel provided with a spring attachment between the nave and the felly. Fig. 7 shows a method of attaching the motor-vehicle to carriages of 25 ordinary construction. Fig. 8 shows an arrangement for transmitting motion to the driving-wheels by means of a jointed shaft. Fig. 9 shows a driving-shaft with a spring-joint. Fig. 10 shows a driving-shaft with a 30 joint of flexible shafting.

Referring to Figs. 1 to 5, Sheet 1, the motor-vehicle frame A is supported on springs on one or two guiding-wheels B and two driving-wheels C. The driving-wheels C run 35 loosely on an axle D, which revolves in bearings E, sliding between horn-plates A' on the carriage-frame A. The bearings E carry springs which support the carriage-frame A. In order that the driving-wheels may not skid 40 when running around curves owing to one wheel revolving more quickly than another, power is conveyed from the axle D to the driving-wheels C by means of clutches C' D', the former forming part of or being secured 45 to the hubs of the wheels C and the latter being provided with a feather sliding in a feather-way on the axle D. The clutches D' are connected by chains F' F² or their equivalents to the axle of the guiding-wheels B, 50 the clutch D' on the "near" side of the motor-vehicle being connected by means of the

chain F' to the "off" side of the fore-carriage or axle of the guiding-wheels and the clutch D' on the off side being similarly connected by the chain F² to the near side of the fore-carriage. By this arrangement when the fore-carriage is caused to revolve on its pivot, so that the motor-vehicle may turn to the right, the chain F² draws the clutch D' on the off side out of gear with the clutch C' on the off 55 wheel C, allowing said wheel to revolve independently of the axle D. In the same manner the near wheel C can revolve independently of its axle D by the similar action of the chain F' when the motor-vehicle is caused 60 to turn to the left. On the motor-vehicle again running a straight course the clutches D' are brought into gear with the clutches C' on the driving-wheels C by means of springs D² on the axle D, between the clutches D' 65 and the bearings E. The chains F' F² pass over pulleys D³, attached to loose collars on the axle D.

In order that the motor-vehicle may more easily be steered by hand, the fore-carriage 70 or fifth-wheel, as shown in Fig. 2, is provided with a ball-race G, thus diminishing friction to a minimum. A steering-wheel H is provided, suitably connected by a chain or otherwise to the fore-carriage.

The motor K, secured to the frame A, is provided with two cylinders K³, one in either side of the crank-shaft L and arranged on a common axis. The cranks are so set that both pistons arrive at the end of their strokes 75 simultaneously, and therefore receive the explosive impulse also simultaneously. By this arrangement the shock of the explosion in one cylinder is neutralized by the shock of the explosion in the other cylinder. In order 80 that the connecting-rods of the two pistons, as these near the crank-shaft L on the inward stroke, may clear one another, one of the connecting-rods K' is forked.

The crank-shaft L is extended on either side 85 of the motor K and is provided with bearings K² in the frame A.

It is obvious that a motor of this construction is applicable to all other purposes where absence of vibration is of advantage.

I do not confine myself to this particular form of arranging the cylinders, for I may

change the position and form of the cylinders with the same form of crank-shaft without departing from the spirit of my invention.

At one end of the crank-shaft L is keyed a 5 chain-wheel or band-pulley L', which carries a straight chain or band driving a chain wheel or pulley M', mounted loosely at one end of a counter-shaft M, running in bearings M² or underneath the frame A. At the 10 other end of the crank-shaft L is keyed a toothed wheel L², gearing with another toothed wheel M³, mounted loosely on the corresponding end of the counter-shaft M. Thus the 15 chain-wheel or band-pulley M' will revolve in a direction opposite to the direction of revolution of the toothed wheel M³, and by alternately connecting the counter-shaft M to one or another of these two wheels it is obvious that the said counter-shaft will revolve in 20 either direction. For this purpose both the wheel or pulley M' and the wheel M³ are provided with a clutch of the following construction: On the counter-shaft M is secured a cross-bar or collar M⁴, affording fixed pivots 25 M⁵, equidistant from the center of the counter-shaft for two or more levers. The ends M⁶ of these levers form a pocket or jaw, into each of which is loosely inserted a roller M⁷. (See Fig. 3.) The other ends M⁸ of these levers 30 are beveled and are operated by a cone M⁹, sliding on the counter-shaft M and provided with a feather which takes into a feather-way on the said shaft. The ends M⁶ of these levers are normally kept apart to the required extent by a spring or springs M¹⁰. On both the 35 chain wheel or pulley M' and the toothed wheel M³ are provided cylindrical bosses M¹¹, upon which revolve the rollers M⁷ in the jaws or pockets M⁶. The action of this clutch is 40 as follows: The cone M⁹ is driven between the ends M⁸ of the levers, expanding these and closing in the jaw or pocket ends M⁶, compressing the spring or springs M¹⁰, and compressing the rollers M⁷ between the bottom 45 of the jaws or pockets and the boss M¹¹ until the friction on the rollers and between the lever ends M⁸ and the cone M⁹ is sufficient to revolve the counter-shaft M. On withdrawing the cone M⁹ the spring or springs M¹⁰ expand, opening out the lever ends M⁸, and thus 50 allowing the rollers M⁷ to revolve freely on the boss M¹¹. The two cones M⁹, are operated simultaneously in such a manner that both cones may be out of gear or one only in gear 55 with their respective lever ends M⁸ at the same time. A convenient means of attaining this object consists of two forked levers N' N², taking into grooves provided on the cones M⁹, being pivoted on the frame A at 60 N³ N⁴, respectively, and connected together by a connecting-rod N⁵. The forked lever N² is bell-cranned to receive a connecting-rod N⁶, which is carried on the front part of the vehicle and operated by a vertical pivoted reversing-lever N⁷, provided with a quadrant. (Not shown.)

The axle D may conveniently be driven at

slow and quick speeds from the counter-shaft M in the following manner: On the counter-shaft M are keyed two chain-wheels or band-pulleys M¹² M¹³, which drive, respectively, by means of chains or bands, two chain-wheels or band-pulleys D⁴ D⁵, mounted loosely on the axle D, provided each with a clutch. The axle D is driven at either rate of speed 75 by means of a double sliding clutch D⁶, provided with a feather taking into a feather-way on the axle D, which may conveniently be put into gear with one or the other of the two chain-wheels or band-pulleys D⁴ D⁵ or 80 thrown out of gear with both by means of a bell-crane lever D⁷, suitably pivoted on the frame A. The lever D⁷ may be operated from the front by means of a connecting-rod D⁸ and a vertical pivoted reversing-lever D⁹, 85 provided with a quadrant. (Not shown.)

In order to prevent the driving-wheels C from slipping, they are provided with a suitable number of links C² of any desirable section, which take over the tires of the wheels 90 C and normally are flush with said tires, but when required and while the driving-wheels C are revolving may be caused to project beyond the surface of the said tires in the following manner:

Referring to Figs. 1, 4, and 5, the links C² are pivoted on one or both sides of the felly or of the spokes, as shown upon the drawings, and on the inner side of the wheel are provided with an arm or extension C³. For each link are provided in the tires two slots C⁴ C⁵. The slot C⁴ is of sufficient depth to permit of the link being flush with the surface of the tire, while the slot C⁵ is of such a depth as to insure the link projecting the required 105 amount beyond the surface of the tire. A spring C⁶ is provided to draw the link into either slot C⁴ or C⁵ when it has passed a position midway between the two slots and also to retain the link in either slot.

Mounted loosely on the axle D are two arms O, which, passing through the horn-plates A', slide therein above the bearings E. These arms extend upward to the level of the top of the driving-wheels C and carry each two sliding pins O' O² and a lever O³, pivoted centrally at O⁴, which operates said sliding pins. The lever O³ may be provided with a handle and moved directly or may be operated in any suitable manner from the front of the vehicle. 115 For example, the lever O³ may be keyed on a rod carried by the arm O at O⁴, said rod being extended to the front of the vehicle and carried there by a swiveling bracket and partially rotated then by a suitable handle or 120 lever.

The links C² normally rest in the slots C⁴; but when the driving-wheels C begin to slip the pin O' is pushed out toward the wheel C by means of the lever O³, thus causing the pin O', as the wheels C revolve, to strike small projections (not shown) on the tops of the links C², throwing them out of the slots C⁴ toward the slots C⁵, the springs C⁶ causing 125

the links to be seated in the slots C⁵, as already described. The distance of the said projections on the tops of the links C² from the center of the axle D being greater when seated in slots C⁵ than when seated in slots C⁴ enables the said projections to pass the pin O' as the wheels continue to revolve.

When the wheels C no longer have a tendency to slip, the position of the lever O³ is reversed, drawing back the pin O' and projecting the pin O² toward the wheel, causing said pin O², as the wheel revolves, to strike the extensions C³ of the links C², thus throwing the links out of the slot O⁵ toward the slot O⁴, the springs C⁶ causing them to be seated in the slot C⁴ level with the periphery of the tire, whereupon the extensions C³ are clear of the pin O² as the wheel continues to revolve.

The mechanism herein described for preventing the driving-wheels from slipping is not claimed in the application in the present instance, but forms the subject-matter of a separate application filed by me on the 19th day of April, 1898, and which bears Serial No. 25 678,194.

Referring to Fig. 6, Sheet 2, the road-wheels may be constructed with one or more coiled or volute springs P, one end of which may be secured to a boss or hub P' on the axle and 30 the other end secured to the felly or rim P² or to an outer nave P³, as shown in the drawings. The outer nave P³ is provided with spokes or disks to connect the same with the felly or rim and cheeks P⁴, which take over 35 two flanges P⁵ on the boss or hub P'. The outer nave P³ is further secured in place by two outer disks P⁶.

In order to make the motor-vehicle applicable for use with carriages of ordinary construction, (see Fig. 7,) the driving-wheels C may be dispensed with, the frame A of the motor-vehicle being hooked on or otherwise coupled to the axle of the leading wheels Q of the carriage. The wheels Q may be provided with suitable chain or band pulleys Q', driven by chains or bands from the counter-shaft M.

Under some circumstances (see Fig. 8) the motion is conveyed from the counter-shaft to 50 two vertical shafts R, one on either side of the vehicle, by means of bevel-wheels M¹⁴ on the counter-shaft, which gear with bevel-wheels R' on the said vertical shafts. The vertical shafts R are broken or divided, the 55 two lengths of each being united by pivoted links R² R³ or by bent springs R⁴, Fig. 9, or by short pieces of flexible shafting R⁵, Fig. 10, by which arrangements allowance is made for the movement of the carriage-body on 60 the springs, the upper portions of the shafts R being supported in brackets on the carriage-body and the lower portions of said shafts being supported in bearings R⁶, secured to the stationary axle S of the driving-wheels C. On the lower ends of the shafts R 65 are provided bevel-wheels R⁷, which gear with bevel-wheels S', running loosely on the

axle S and attached to or forming part of the hubs of the driving-wheels C.

I claim—

1. A motor-vehicle provided with two cylinders arranged opposite each other of which the piston of one is connected to one of the cranks of a crank-shaft with three cranks, two of which are opposite to the third crank, 75 while the other piston is connected to the other two cranks in such manner that both pistons receive a simultaneous impulse and approach and recede from each other simultaneously and so that the shock or vibration resulting from the impulse in one cylinder is neutralized by the shock or vibration resulting from the impulse in the opposite cylinder substantially as set forth.

2. A motor-vehicle provided with two cylinders arranged opposite each other of which the piston of one is connected to one of the cranks of a crank-shaft with three cranks, two of which are opposite to the third crank while the other piston is connected to the two 90 other cranks in such manner that both pistons receive a simultaneous impulse and approach and recede from each other simultaneously, gearing for communicating motion from the crank-shaft to the road driving-wheels; clutches for putting said gearing in and out of gear for going forward or backward or stopping, gearing and clutches for varying the speed of the road driving-wheels and means for steering the vehicle substantially as described and shown.

3. A motor-vehicle provided with two cylinders K⁸ K⁹ arranged opposite to each other of which the piston of one is connected by a connecting-rod K to one of the cranks of a 105 crank-shaft L while the other piston is connected by a forked connecting-rod K' to the other two cranks, gearing for communicating motion from the crank-shaft to the road driving-wheels C C consisting of a chain-wheel 110 L' a chain and a chain-wheel M' mounted loosely on a counter-shaft M and a spur-wheel L² gearing with a spur-wheel M³ also mounted loosely on the counter-shaft, two clutches sliding on and revolving with the counter-shaft and connected together so that either 115 may gear with or not gear with the chain-wheel M' or spur-wheel M³ respectively to cause the counter-shaft to revolve in either direction or not to revolve, two chain-wheels 120 mounted on the counter-shaft and communicating motion by chains to two other chain-wheels D⁴ and D⁵ on the axle of the road driving-wheels, a clutch D⁶ sliding on and revolving with the said road-driving-wheels' 125 axle, means for causing the said clutch D⁶ for gearing with either or neither of the chain-wheels D⁴ or D⁵, clutches D' D' operated by the turning of the fore-carriage to cause one of the road driving-wheels to be capable of 130 independent revolution when the vehicle turns and means for steering substantially as described and shown.

4. In a motor-vehicle, the combination of a

shaft, a wheel loosely journaled on said shaft and having a projecting hub, a clutch mechanism consisting of a collar fixed on said shaft, a lever pivoted to said collar and adapted to bear at one end on said hub, a ball mounted in the end of said lever bearing on said hub, and means for operating said lever.

5. In a motor-vehicle, the combination of a shaft, a wheel loosely journaled on said shaft and having a projecting hub, a clutch mechanism consisting of a collar fixed on said shaft, a lever pivoted to said collar and adapted to bear at an end on said hub, a ball mounted in the end of said lever bearing on the hub, 15 a cone sliding on said shaft, and means for forcing said cone beneath the free end of said lever.

6. In a motor-vehicle, the combination of a driven shaft, a gear-wheel and a sprocket-wheel mounted on said shaft, a counter-shaft, a gear-wheel loosely journaled on said counter-shaft and meshing with the gear-wheel on said driven shaft, a sprocket-wheel loosely journaled on said counter-shaft, a chain con-

necting said sprocket-wheels, clutch mechanisms for connecting with the counter-shaft either the sprocket-wheel or the gear-wheel journaled thereon, and means for operating said clutch mechanisms.

7. In a motor-vehicle, the combination of a driven shaft, a gear-wheel and a sprocket-wheel mounted on said driven shaft, a counter-shaft, a gear-wheel loosely journaled on said counter-shaft and meshing with the gear-wheel mounted on the driven shaft, a sprocket-wheel loosely journaled on said counter-shaft, a chain connecting said sprocket-wheels, clutch mechanisms for connecting with the counter-shaft either the gear or sprocket wheels loosely journaled thereon, means for 35 operating said clutch mechanism, a driving-shaft, and mechanism for conveying motion from said counter-shaft to said driving-shaft.
